US00D953364S

(12) **United States Design Patent** (10) Patent No.: **US D953,364 S**
(45) Date of Patent: **** May 31, 2022**

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Erica L. Clymer**, Northampton, PA
(US); **Praneetha Jonnala**, Allentown,
PA (US); **James Mathias Weber**,
Allentown, PA (US); **Jennifer Wong**,
Breinigsville, PA (US)

(73) Assignee: **Lutron Technology Company LLC**,
Coopersburg, PA (US)

(**) Term: **15 Years**

(21) Appl. No.: **29/768,074**

(22) Filed: **Jan. 27, 2021**

Related U.S. Application Data

(63) Continuation of application No. 29/732,187, filed on
Apr. 22, 2020, now Pat. No. Des. 914,740, which is
a continuation of application No. 29/689,882, filed on
May 2, 2019, now Pat. No. Des. 883,321, which is a
continuation of application No. 29/621,353, filed on
Oct. 6, 2017, now Pat. No. Des. 848,471, which is a
continuation of application No. 29/575,797, filed on
Aug. 29, 2016, now Pat. No. Des. 802,622.

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design. The interior broken lines illustrate portions of the graphical user interface which form no part of the claimed design.
